UNITED STATES PATENT OFFICE.

EDWARD BEECHER, OF ST. LOUIS, MISSOURI, ASSIGNOR TO MCQUAY-NORRIS MANUFACTURING COMPANY, A CORPORATION OF MISSOURI.

PISTON-RING.

1,348,146.

Specification of Letters Patent.

Patented Aug. 3, 1920.

Application filed September 3, 1918. Serial No. 252,421.

To all whom it may concern:

Be it known that I, EDWARD BEECHER, a citizen of the United States, residing at St. Louis, State of Missouri, have invented certain new and useful Improvements in Piston-Rings, of which the following is a full, clear, and exact description, reference being had to the accompanying drawings, forming a part hereof.

- 10 The present invention is directed to improvements in piston-rings for use in cylinders of internal combustion engines, and particularly to the closed joint type of split metal ring, the object being to provide a ring 15 which shall at all times be free to expand against the inner walls of the cylinder in which the piston operates, and one in which the terminals of the ring by which the joint is formed are so shaped as to guide and assist 20 one another in the contracting or closing movement of the ring to permit the latter to be inserted into the cylinder. The ring as constructed possesses structural features the advantages of which will be apparent from 25 the following detailed description in connection with the accompanying drawing in which—

Figure 1 represents a middle longitudinal section of a gas engine cylinder with the piston 30 in elevation showing the improved ring applied thereto; Fig. 2 is an outer face view of the ring when free or expanded; Fig. 3 is an outer face view of the ring when contracted to close the joint between its terminals; Fig. 4 is an end view of one terminal; Fig. 5 is an end view of the opposite terminal; Fig. 6 is a cross-section on the line 6—6 35 of Fig. 2; Fig. 7 is a side view of the ring when free or expanded; Fig. 8 is a side view 40 of the ring in its contracted or operative position; and Fig. 9 is a perspective view of the ring when free.

Referring to the drawings, G represents the engine cylinder, and P the piston which, 45 in the present example, is shown as equipped with two of the improved rings. The ring comprises a resilient split band 1 preferably of uniform cross-section, the ends of the band being normally disengaged when the 50 band is free or in the open (Figs. 2, 7, and 9). As well understood in the art the band is received by a peripheral groove h formed in the piston (Fig. 1). The ends of the band terminate in tongues or extensions t, t, dis- 55 posed respectively contiguous to the opposite

sides of the band, the width of each tongue being substantially one-half the width of the band (the width being the dimension measured parallel to the axis of the band), and the thickness of each tongue being substantially one-half the thickness of the band (the thickness being the dimension measured radially from the center of the ring). The length of the tongue t is determined by the position of the inner terminal transverse 60 abutting end or edge e offset radially from the base of the tongue as shown, the depth of the offset being substantially one-half the thickness of the band. The inner contiguous corners c of the free ends of the tongues are 65 rounded or convexed inwardly or toward one another as shown, for a reason presently to appear. Formed on the outer face of the band, and leading from each edge e to a point beyond the tongue and contiguous to 70 the side of the band opposite from that of the tongue is a recess or depression d, the depth of which is substantially equal to the thickness of the tongue, and its length to the length of the tongue, the bounding edges or 75 walls of a depression being curved to conform to the corresponding edges of the tongue opposite thereto, so that when the band is contracted or compressed by a movement of its separated ends toward one another in the general plane of the band, the 80 tongues will be received by their corresponding depressions, and the edges e, e, (which are preferably parallel to the axis 85 of the band or perpendicular to the sides of the band) will be brought into abutting relation, the outer faces of the tongues being continuous and coincident or flush with, the outer face of the band. It will be seen from the foregoing that as the band is being compressed or contracted from its free condition, the sloping surfaces formed by the rounded corners c, c, will guide the respective 90 tongues in their movement over one another, causing the inner edge of one tongue to ride 95 over the corresponding edge of the opposite tongue without danger of the tongues fouling in such a way as to arrest the contracting movement of the band. It will be seen that the depression d contiguous to one 100 tongue is shaped to receive the opposite tongue, the curvature of the bounding walls of a depression being the reverse of the curvature of the rounded edge of the tongue contiguous thereto, whereby the two curva- 105 110

tures form a reverse curve in the shape of an elongated letter **S**. The extent of the contracting movement of the band necessarily depends on the length or circumferential dimension of the depression *d* and the length of the tongue *t* which the same is designed to receive, and this without regard to the angle which the ends or edges *e* make with the sides of the band, said angle in the example shown being a right angle though obviously I am not to be limited to this angle. The parts are so proportioned that when the tongues *t* have fully entered their respective recesses or depressions *d* the edges *e*, *e*, are brought substantially into abutting or contiguous relation.

The offsets forming the edges *e*, and the curved bounding walls of the recesses or depressions *d* are substantially radial in direction so that the ends of the ring when compressed into the cylinder in which the piston is to operate are free to expand outward and permit the outer face of the ring to hug the inner walls of the cylinder. The rubbing or coacting surfaces of the bottoms of the depressions *d* and the inner faces of the tongues *t* are concentric with the inner and outer faces of the ring so that the ends of the ring are free to play over one another in their contracting and expanding movements. Again, if in the contracting movement of the ring the same should be distorted or sprung laterally or out of the plane of the ring so as to cause one tongue to foul the opposite tongue, the rounded corners *c* will properly guide the tongues into their respective depressions or recesses *d* as clearly obvious from Figs. 2 and 3 of the drawings. The ring may of course be used on any type of internal combustion, steam, air or other engine, not being restricted in its use to any one type.

It will be seen from the foregoing that each tongue or extension *t* constitutes an outer terminal member with an outer face continuous with the outer face of the band, said tongue being contiguous to one side of the band; that the edge *e* constitutes an inner formation offset from the base of the tongue; that the recess or depression *d* leading from the edge *e* faces outwardly and is located contiguous to the opposite side of the band, the curved bounding wall of the recess being equal in depth substantially to the depth of the offset forming the edge or end *e*; that the tongue and recess at one end are diagonally opposite the tongue and recess at the other end, whereby upon compression of the band each tongue slips into its respective recess. In other words, the tongue and depression at one end of the band are formed reversely to the tongue and depression at the opposite end, the transverse abutting edges *e*, *e*, being disposed midway between the terminals of the reverse curves defining the

curved portions of the tongues and curved bounding walls of the depressions aforesaid. This permits a lap-joint to be formed between the tongues *t*, *t*, and an abutting or butt joint between the edges or ends *e*, *e*, there being a lap joint on each side of the butt joint thus formed. Obviously the ring may be modified in many particulars without departing from the nature or spirit of the invention.

Having described my invention what I claim is:

1. A one-piece piston ring comprising a resilient split metal band having its ends disengaged when free, and terminating in transverse abutting edges extending the width of the band contiguous to the inner face of the band, tongue extensions on the outer face of the band having inner sloping corners at their free ends and projecting beyond the transverse edges aforesaid disposed respectively contiguous to the opposite sides of the band, an outwardly facing depression leading from each transverse edge in an opposite direction from the tongue, the band being contractible by a movement of its free ends toward one another in the general plane of the band, whereby a tongue at one end, in such contracting movement, is received by and guided into the depression opposite thereto at the other end, the transverse edges aforesaid being brought into contiguous relation with a complete closing of the band.

2. A one-piece piston ring comprising a resilient split metal band terminating in transverse abutting edges extending the width of the band contiguous to the inner face of the band, tongue extensions on the outer face of the band having inner rounded corners at their free ends and projecting beyond the transverse edges aforesaid disposed respectively contiguous to the opposite sides of the band, an outwardly facing depression leading from each transverse edge in an opposite direction from the tongue, the band being contractible by a movement of its free ends toward one another in the general plane of the band, a tongue at one end in such contracting movement being received by and guided into the depression opposite thereto at the other end, the abutting edges aforesaid being substantially midway between the free ends of the tongues and the inner terminals of the depression leading from said edges.

3. A one-piece piston ring comprising a resilient split metal band terminating in straight abutting edges disposed across the band contracting and expanding in the general plane of the band and at right angles to the sides of the band and contiguous to the inner face of the band, and of a thickness substantially one-half the thickness of the band, a tongue at one end disposed on one

- side of the band along the outer face of the band and extending beyond the straight edge at said end, a corresponding tongue at the opposite end disposed on the opposite side of the 5 band along the outer face of the band and projecting in the opposite direction to the first named tongue, an outwardly facing depression having a depth substantially equal to one-half the thickness of the band leading 10 from each straight edge in the opposite direction from the tongue projecting from said edge to a point removed from the edge a distance equal to the length of the tongue, the depression at one end being opposite to 15 the tongue at the other end the inner free edges of the tongues being convexed toward
- one another and the depressions having their bounding walls curved to conform to the shape of the tongues to receive the respective tongues, the combined curve of a 20 tongue and bounding wall of a depression forming a reverse or S-shaped curve disposed symmetrically on opposite sides of the straight edge in which the band terminates, the parts operating substantially as and for 25 the purpose set forth.

In testimony whereof I affix my signature, in presence of two witnesses.

EDWARD BEECHER.
